UNITED STATES PATENT OFFICE.

JAMES EDWARD O'BRIEN, OF HINTON, WEST VIRGINIA.

DESIGN FOR A COMBINATION ASH-TRAY AND CIGAR-HOLDER.

57,541.

Specification for Design.

Patented Apr. 12, 1921.

Application filed June 11, 1920. Serial No. 388,365. Term of patent 3½ years.

To all whom it may concern:

Be it known that I, JAMES EDWARD O'BRIEN, a citizen of the United States, residing at Hinton, in the county of Summers and State of West Virginia, have invented a new, original, and ornamental Design for a Combination Ash-Tray and Cigar-Holder, of which the following is a specification, reference being had to the accompanying drawing, forming a part thereof.

Fig. 2 is a plan view thereof.

I claim:

The ornamental design for a combination ash tray and cigar holder as shown.

JAMES EDWARD O'BRIEN.
